CLAIM

The ornamental design for reticle for a telescopic gun scope, as shown and described.

DESCRIPTION

FIG. 1 is a front perspective view of a reticle for a telescopic gun scope;

FIG. 2 is a front view thereof, the rear view being a mirror image of the front view thereof;

FIG. 3 is a left view thereof, the right view being a mirror image of the left view thereof; and,

FIG. 4 is a top view thereof, the bottom view being a mirror image of the top view thereof.
